UNITED STATES PATENT OFFICE.

GOTTHILF ANSGARIUS BETULANDER, OF SÖDERTÖRNS VILLASTAD, AND NILS GUNNAR PALMGREN, OF STOCKHOLM, SWEDEN, ASSIGNS TO THE BETULANDER AUTOMATIC TELEPHONE COMPANY LIMITED, OF LONDON, ENGLAND.

SELECTING DEVICE FOR AUTOMATIC OR SEMI-AUTOMATIC TELEPHONE SYSTEMS.

1,205,700.

Specification of Letters Patent. Patented Nov. 21, 1916.

Application filed June 26, 1914. Serial No. 847,495.

To all whom it may concern:

Be it known that we, GOTTHILF ANSGARIUS BETULANDER, a subject of the King of Sweden, and resident of Villa Castor, Söder-törns Villastad, in the Kingdom of Sweden, and NILS GUNNAR PALMGREN, a subject of the King of Sweden, and resident of 35 Tjärhofsgatan, Stockholm, in the Kingdom of Sweden, have invented certain new and useful Improvements in Selecting Devices for Automatic or Semi-Automatic Telephone Systems, of which the following is a specification, reference being had therein to the accompanying drawings.

15 The invention relates to line selecting devices for automatic or semi-automatic telephone systems and more specially to selecting devices which consist of relays, and the selecting relays of which are affected in correspondence with the engaged or disengaged condition of the appertaining line.

The object of the invention is to simplify selecting devices of that class. This is attained according to the invention by only 25 one selecting relay being assigned to each selecting stage, the operating circuits of the selecting relays being controlled by a common relay adapted to prevent the affecting of the selecting device by the selected line 30 being marked as engaged.

The figure shows one form of the invention as applied to a telephone system in which the connections are effected by means of relays.

35 In the example shown in the drawing a talking line 1 is adapted to be connected with any of a number of lines 2, 3 and 4 by means of relays 5, 6 and 7 and contacts 8, 9 and 10 respectively. The selection of a 40 disengaged line 2, 3 or 4 is effected by means of a selecting device consisting of a series of selecting or testing relays 11, 12 and 13 one selecting relay being provided for each line 2, 3 and 4. The operation of 45 the selecting device is controlled by a set of common relays 14, 15 and 16. Each selecting relay has two windings viz. a test winding 17, connected with the test wire 18 of the corresponding line 2, 3 or 4, and a locking winding 19. A line 2, 3 or 4 is 50 marked as engaged by earth being connected to the test wire 18 through a contact 20 of a connecting relay 5, 6 or 7.

Although only one line 1 is shown, yet it

is supposed that the lines 2, 3 and 4 are 55 common to a plurality of lines 1.

When the line 1 is to be connected with one of the lines 2, 3 or 4, a contact 21 is first closed. This causes a flow of current from the earthed pole of a battery 22 through relay 14, contact 23 of a relay 24, assigned to the line 1, and contact 21 to the negative pole of the battery. The relay 14, upon energizing, closes the contact 25 thereby effecting the energization of those of the selecting relays, corresponding to engaged lines 2, 3 or 4, over circuits including contact 20, wire 18, winding 17, contact 26 of relay 16 and contact 25. In this instance it may be assumed that the line 2 is engaged. 70 The selecting relay 11 is, consequently, energized while the relays 12 and 13 remain de-energized. The relay 11 upon operating cuts in its locking winding 19 through contact 27. Upon the closure of the contact 25 also relay 75 15 was energized whereby relay 16 was cut in through contact 28. The relay 16 therefore opens the operating circuits of all selecting relays at the contact 26. The connection with the first disengaged line 3 is 80 now established through the mediation of the relay 24 which is energized through contact 28, contact 29 and contact 21 and is locked over its contact 30. A circuit is thereby closed extending from earth through 85 contact 28 of relay 15, contact 31 of relay 11, contact 32 of relay 12, wire 33, relay 6, contact 34 of relay 24 and contact 21 to the battery. The connecting relay 6 energizes upon the closure of that circuit and is locked 90 over its contacts 35 and 20. The line 1 is thereby connected with the line 3 through contact 9 of relay 6 and the connection is then maintained as long as the contact 21 is closed. Although the test wire 18 of the 95 line 3 is connected to earth in the moment of establishing the connection, yet the corresponding selecting relay 12 is not thereby affected as the operating circuits of the selecting relays are open at contact 26 of relay 16. The relay 16, therefore, prevents disturbances which else might be caused by the selected line being marked as engaged in the connecting moment. Disturbances which might occur on account of a line being disengaged in the connecting moment, are prevented by the selecting relays being 100 locked over circuits (27, 25, 22) independent

of the engaged and disengaged condition of the lines 2, 3 and 4.

At the opening of contact 23 the relays 14, 15 and 16 are deenergized successively the selecting device being thereby restored into normal condition. The connection between lines 1 and 3 is severed by opening the contact 21 the relays 6 and 24 being thereby deenergized.

10 The selecting device is shown as allotted to only one line 1 but it may also be used in well-known manner in common by a plurality of lines.

Having now described our invention, 15 what we claim as new and desire to secure by Letters Patent is:

1. A non-numerical selecting device consisting of relays and comprising one selecting relay for each selective position, operating circuits for said relays including means for marking the selective lines as engaged, and a common relay controlling the operating circuits of said relays so as to

prevent re-operation of the selecting device by a selected line being marked as engaged. 25

2. A non-numerical selecting device consisting of relays and comprising one selecting relay for each selective position, operating circuits for said relays including means for marking the selective lines as 30 engaged, holding circuits for said relays independent of the condition of the selectable lines, and a common relay controlling the operating circuits of said relays so as to prevent re-operation of the selecting device by a selected line being marked as engaged. 35

In witness whereof, we have hereunto signed our names in the presence of two subscribing witnesses.

GOTTHILF ANSGARIUS BETULANDER.
